UNITED STATES PATENT OFFICE

1,994,183

ART OF ICE MAKING

Douglas Kent Warner, Bristol, Conn.

Application January 16, 1930, Serial No. 421,185

13 Claims. (Cl. 62—105)

This invention relates to improvements in the process of the manufacture of ice by what is known as direct expansion, which means evaporation of the liquid refrigerant directly adjacent to the water being frozen as compared with the usual practise of first cooling brine, and with it freezing water. One manner of so freezing ice was shown in application of Nov. 9, 1927 becoming Patent No. 1,884,428 issued Oct. 10, 1932. This method has been combined with apparatus shown in application filed April 20, 1928 Serial No. 271,632 which was later combined with application Serial No. 277,931 and issued in Patent No. 1,928,580 together with several new improvements presently to be disclosed, to make a cheaper and more efficient plant. The purpose of the improvements are to permit of thawing the ice loose from the can walls with a minimum number of valves, a minimum of labor, and a minimum loss of refrigeration. The last object is obtained by not using condenser gas for thawing, but using instead, gas generated by initial cooling of the can water and the precooling of the liquid refrigerant. The minimum number of valves is attained by using three-way cocks of special design and a new, non-gas return, float ball check, which permits the liquid to be rapidly forced out of the can walls and when out, sinks and checks escape of gas, but still permits a very small stream of liquid to run out as it is condensed by the thawing of the ice. Another improvement is in the method of preventing ice formations catching at the openings in the bottom of the can where the water is either circulated in or out. This is accomplished by doing no freezing at the bottom of the can but instead condensing some gas there a few hours before pulling time and again when thawing, this being accomplished without any extra labor operations.

The invention may be better understood by referring to the drawings in which sheet one Fig. 1 shows a cross section thru the ice tank, the liquid circulating and gas separating pipes, the intermediate pressure liquid receiver and water and ammonia forecooler, the condenser and compressor and two necessary float valves such as shown in my Patent No. 1,761,000 issued June 3, 1930. Fig. 2 shows a plan of the top 50 of the tank; Fig. 3 is a section of the can wall. Fig. 4 sheet two shows a section of another tank, the compressor and condenser not appearing. Fig. 5 is a part plan and part section of another single can. Similar numbers refer to similar 55 parts in the various figures. Fig. 6 represents

a float check valve the purpose of which is to automatically drain liquid from the evaporator while the latter is being thawed without permitting any considerable amount of warm vapors to be passed out with the liquid. Letter *x* represents a very light hollow steel ball which floats in the liquid refrigerant. Element *y* is a metal baffle fixed in the valve for the purposes of limiting the distance upwards which ball *x* may travel. Valve port 63 drains liquid while ball *x* is up. While the liquid is being forced downward thru the valve by the thawing vapors the ball floats and permits rapid escape of the liquid thru the main orifice 63 and also thru a small hole 61. As soon as the liquid is out the ball *x* drops and closes the main outlet while the small hole 61 remains open to carry off additional refrigerant condensate from the thawing process which would otherwise be trapped above the ball as the ball buoyancy would not suffice to lift it from the seat once it had dropped and a pressure difference had been set up across the port 63. Removal of the thawing vapor pressure and reversal of liquid flow to freeze a new ice cake again lifts the ball *x*.

In Fig. 1 gas is compressed in compressor 6 and flows to condenser 1 and the outside of water-cooled tubes B. Liquid drains to high pressure float valve 2, the float rising drains all the liquid without breaking the seal into receiver 3 and the pressure in 3 forces the liquid on up to constant level float valve 4, which is similar to the first valve only upside down. At a predetermined level its float rises and shuts off the liquid. Drum 5 is maintained about half full of liquid and this liquid circulates by gravity or power thru down pipe 7 and lower header 8. Liquid rises thru valve 9 and pipe 10 to the lower section of the end can wall. It passes thru the lower section of can walls 12 and up passages 41 between the electric roll welded seams 13 to upper section 14 and thence thru valve 15 back to evaporating drum 5 where part of the liquid evaporates due to the heat gained in circulation thru the ice freezing walls and the balance of the liquid recirculates as before.

The gas passes off thru pipe S' to the suction valves of the compressor. The liquid passing between the float valves cools itself by liberating gas into the receiver 3. This receiver also absorbs the variations in flow of the two valves and in addition houses the pipes A for the make up water which is cooled by passing thru them. The intermediate pressure gas passes off thru pipe 16 and pressure regulating valve 50 to a

multiple effect port 62 on the compressor 6. Here it compresses the low pressure gas which the cylinder has previously sucked in thru S and the whole is further compressed and sent to 5 the condenser 1. When thawing, part of the intermediate pressure gas passes thru pressure regulating valve 51 to hand valve 17. Thence it passes thru the partitions in the bottom of the can and around the water openings 36 and 37 10 back thru pipe 18 to the top and end of the can wall thru passage 14 down thru 41 and out thru 12, 10 and 9 to the liquid pipe 8. The liquid valve 9 must be nearly closed so that the gas pressure may build up enough to thaw the ice 15 but still permit the condensed liquid to escape. In Fig. 4 an automatic valve 29 does this work. A hollow ball lighter than the refrigerant floats up away from its seat while the pipe is full of liquid. When liquid is being blown back out 20 the baffle y protects ball x from being carried back down to its seat. When the liquid is all out the ball settles on its seat and could not again be lifted by the liquid until the pressure has been removed from above it. 25 For this reason a small hole is drilled thru its seat sufficient to pass off the required liquid without letting much gas escape. During the thawing valves 15 or K have been closed to the drum 5. In Fig. 4 valve 17 is operated by a pull rod P 30 and handle N. Pipe 18 instead of passing at once into the can wall goes to the three-way cock K. In operating, valve 17 is opened 3 or 4 hours prior to thawing time. Gas passes into walls D, E, F, G, and H until condensation has entirely filled the 35 space with liquid. Then no more thawing can take place until valve K is opened to 18 and closed to gas liberating header 5. This condensation has been sufficient to prevent the ice building out around the lip of 39 and still has not caused a core 40 to be formed at the bottom of the cake. The bottom of the can is divided on its center line so that if the bottom should freeze across before the upper portion, trapped water can do no damage in freezing as the can wall can move out. 45 The double thawing keeps the bottom open till the rest is frozen and so keeps up a rapid agitation in the water space as long as any water is left, permitting coreless ice. The ice being as thick at the bottom as at the top it all freezes at about 50 the same time and the 7 hour wait while the last inch is freezing at the top of the ordinary block is eliminated and with it go two other important losses. The first is that the long wait permits the lower part of the block to absorb much refrigeration in unnecessarily lowering its whole 55 temperature to that of the cooling medium and the second is that having become so cold it thaws very slowly and much ice is melted from the top of the cake while waiting for the bottom to loosen. 60 No taper is needed on these cans for the water coming up thru the big passages 36 and 37 lifts and follows after the ice as it is pulled and the long can walls could easily bend out if necessary to 65 the open water on the side where the ice has just been pulled.

The water is circulated in the cans by means of the revolving tube 32 which runs the length of the tank and circulates the water in all the cans with the aid of a paddle 33 on each side of it. The 70 paddles come in close contact with the shell 44 and the water is forced around with the paddles causing a continuous stream of water to flow to the right at the bottom of shell 44. This draws other water from the tank 30 below the cans

with it thus effecting the circulation of water. The paddles also effect little pulsations in this flow by throwing a little more water as they pass the edge of opening 36. This gives the necessary 5 jolt to sweep the air bubbles and dirt loose from the ice walls. Where the ice is nearly frozen less water can pass but the surplus water readily passes along to the cans where the ice has just begun to freeze.

In air agitating systems the same power is 10 devoted to agitating 30 lbs. of water in the can as when there is 300 lbs. in it, though it obviously 15 needs only one tenth as much, so that in order to have the required agitation during the first hour nearly 10 times too much power is used the other 39 hours. Air agitation being inefficient at best a decided gain is made by changing to water agitation and a clear ice from the poorest water is 20 possible just as the ice is formed clear in fast running streams.

The construction shown saves freezing time by 25 eliminating ice taper and delay in freezing where a thick top end of the cake is required because of uneven thawing means and lack of positive removal means. Less can metal is required for it 30 also.

The space between cans being eliminated a 35 further great saving in the cost of the building is involved. Other savings are the cost of the brine tank, air compressor, air laterals and system, can 40 dump, can fillers, dip tank, core pump, core suckers, etc., but more particularly the labor saved by eliminating the above mentioned articles and the requirement of slowly thawing an air tube 45 from every ice cake.

As in former disclosures the water from the bottom of the tank in front of baffle 20 is being continually drawn off thru 21 and pump 22, three-way clean-out cock 26, sand filter 23, and back to tank 30 thru second three-way cock 25 and 50 pipe 24.

Only one side wall of one can is thawed at a time. The other side which had been thawed for the previous cake is left with both the freezing 55 valve K and thawing valve N closed until the adjacent cake is pulled, when freezing is commenced again on one side of the cake just pulled. Each can wall and every bottom is a separate unit and any one may be pumped out and replaced 60 without disturbing the others or taking the gas out of them. One side and two end walls together with a bottom strip under the wall 2 inches wide make a can wall assembly unit. It is made of two, ten by four ft. 12 gage cold rolled steel sheets 65 spot or roll welded together at marks 13, the passages 12 and 14 being left unwelded and un-stamped so as to permit the refrigerant to travel across the tank. The top edges are arc welded together, a diamond shaped plate being welded over the top of the marking grooves. These plates support the can covers which in turn support the lifting hooks T. The lifting hooks consist of a single strip of flat German silver or other high resistance metal with an eye at either end 70 to engage with a double pointed crane hook. The high resistance strip extends down into the water on one side of the can center line and back up on the other side with about a $\frac{1}{4}$ inch space between the two so that it would be possible to thaw, 75 by the needle hot water method, in case electricity was not available for the purpose at any time. The hooks are left in the ice during storage and until the ice is set on the scoring machine. The pulling crane takes the ice directly 80

to its place in the store room and also back to the scoring table. It lowers the ice while it is being scored vertically in the grooves on one side only. Then a low voltage current is turned 5 on to the double pointed crane hooks permitting the current to pass into the ice hook thru one eye and back through the other. The high resistance soon loosens the hooks by the heat formed and the hooks are pulled up by the crane. The 10 ice is then tipped down onto the scoring table with the vertically scored side at the bottom. Conveyor chains now carry the ice sheet lengthwise between upper and lower banks of saws located at the center of the table at the outer wall 15 of the building. As the ice is sawed it passes thru the wall opening, onto the outer half of the table and directly onto the truck. The sheets are frozen in lengths so as to just fit the average truck or about 1500 lbs. per sheet. Usually two sheets 20 make a load and before the second sheet comes out the truck driver raises the outer edge of the table which is pivoted at its center and the second cake slides easily on top of the first. The ice being scored both ways on the bottom the driver 25 has only to touch the top groove or score mark with his pick to break the ice where he desires. The shrinkage and breakage during delivery is reduced by keeping the ice all in one piece. The driver need not know how to cut ice or handle 30 the big cakes on the platform. His only duty is to politely deliver pieces of ice, all exactly uniform in dimensions. His troubles in getting the thick ends of a cake into an ice box a little too small are over. His time of cutting and loading the 35 ice saved, so that in a given time he can deliver twenty percent more ice, increasing his earnings accordingly. The manufacturer is not faced with the difficult proposition each summer of finding skilled and honest ice cutters, and not being required to move heavy ice blocks a light man can 40 do the work easier than a heavy man since about 80% of the work done is carrying the man's own weight around and up and down the stairs.

The process of building these tanks consists of 45 welding separately the bottom continuous passage, and the three walls of a can unit. After welding these are each tested air tight under pressure and then galvanized. Where each piece is to be welded to the next, a single strip of metal 50 extends almost an inch beyond the double section. The edge of this strip is dipped in acid to remove the galvanizing. It is then bead welded on the outside and soldered smooth on the inside and zinc sprayed, or painted over the weld on 55 the outside of the can. The bottom section consists of a double welded sheet starting at D passing around opening 36 at E, being cut away at the end of E to permit the blades of agitator 32 to revolve. A small passage for the gas is still left 60 and the sheet is now turned up horizontally at F its lower edge now being brought up to the center line of the can. It continues in this position for various distances depending on the length of cake desired for the delivery trucks used. Then 65 it bends down again at 39 for opening 37 where the circulating water leaves the can. It passes around this opening, is bent back up to reach the center of the can thus forming a split but continuous bottom. It then passes around the 70 inlet water opening similar to the other side E to the outlet opening at H. Short nipples are welded into D and H, and these pass out thru stuffing boxes in the tank wall and are then flanged to their respective pipes. These bottom 75 strips are welded at V to the bottom strip of the

can wall. If the bottom must be replaced the weld V is cut, the flanges unscrewed from the nipples, and the bottom drawn up thru the can, a new bottom sheet inserted and soldered at V. Columns 27 support the can walls and hold 5 the bottom sheets in place, holding both down while the ice is being pulled. If a leak developed in a bottom or a can wall, valves 17 and K would be closed to 3 and 5 and valve 38 would be closed to 8 and the connection opened to pump 10 out the ammonia. It would then be left till an off peak season, ice being pulled from this particular cell only half as often since now only half a block would freeze from one side in the regular period and when the adjoining cake was being 15 thawed this half could either be pulled for 5 inch ice or pushed over to the other side to wait till another half froze.

Agitator 32 is made of a tube the full length of the tank driven by a shaft extending thru the tank at one end and fixed in a bearing at the other end. The ends of the tube are sealed and its weight including the paddles 33 is such that the water just supports it so permitting a long agitator without any bending strains or loads 20 on the bearings.

A 32 ft. tank would be divided into 36 cells freezing 10 inch ice. Assuming the trucks to be 8 ft. long and the ice 46½ inches high the tank would make 20 tons of ice per day with an 30 ammonia suction pressure of 32 lbs. A cake of ice must be pulled every 50 minutes. It is desirable that the thawing temperature thus be adjusted so that the next cake may be started thawing at this time and just be ready to pull 35 when the man comes back fifty minutes later. This may be closely regulated by adjusting pressure regulating valve 50. In winter the flow of gas would need to be checked at 50 on account of the smaller amount of work to be done 40 in forecooling ammonia and feed water and in summer in small plants where the pulls are about an hour apart and a 34 deg. temperature is sufficient for thawing, it might be desirable to reduce the pressure formed either by reducing 45 valve or a connection to another multiple effect port further along in the ammonia cylinder, both ports being kept open in summer and only a small one at the very end of the stroke open in winter.

The pressure regulating valves may be either automatic or hand operated as hand operation would require very little attention, and there would be no great loss even if the ice thawed 55 loose considerably before the pulling time as the low temperature could melt little ice and what was melted would not lower the overall efficiency below that of single stage compression without any thawing. The method of thawing has another advantage in addition to its efficiency. The pressure in the can walls is limited to between 50 to 60 lbs. whereas with condenser gas the pressure would be very variable and might go to 250 lbs. This therefore permits of greater spacing and fewer welded seams in the can walls.

To operate the tank in Fig. 4 rod N is pulled up opening valve 17 three hours before pulling time. It is left up until K has been opened and the ice thawed loose. The ice is pulled and K or 17 closed but K is kept closed and not reopened until the cake of ice adjoining on the other side has been pulled. The cover is lifted with the ice and the only other operation consists of putting it back on the can and inserting two ice hooks 70 75

in its slots. Each time a cake is pulled the man closes a pair of valves K and N and opens another pair, four operations requiring 10 seconds time.

5. What I claim as my invention and desire to secure by Letters Patent, is:

1. A process of thawing ice consisting of producing a refrigerant gas at a pressure between that in the condenser and the main evaporator 10 by evaporating liquid leaving the condenser, by its own heat and then condensing said gas on the evaporator surface.

2. A process of thawing ice for easy removal from evaporator surface by evaporating liquid refrigerant with the heat of water to be used in the making of the ice and conveying the heat in the form of refrigerant vapor at a pressure intermediate between that in the condenser and evaporator and condensing said vapor on the evaporator surface in such manner that the ice water is cooled preliminary to being frozen by supplying the heat for evaporating liquid to thaw the ice.

3. The process of manufacturing ice in containers in the walls of which the refrigerant is evaporated and later condensed for thawing the ice loose, which consists of producing vapor for thawing the ice by a combination of liquid evaporation caused by reducing the pressure of the liquid refrigerant leaving the condenser, thereby cooling this liquid, and liquid evaporation caused by absorbing heat from the water to be used in ice making.

4. The process of manufacturing ice in containers in the walls of which the refrigerant is evaporated for freezing ice and condensed for thawing ice loose, the vapor for thawing the ice loose being produced by evaporation of refrigerant in absorbing heat from the liquid refrigerant and from the water to be used in ice making, and said thawing vapor having its pressure held approximately constant at a desired pressure intermediate between that in the condenser and evaporator by a pressure reducing valve admitting surplus vapor into the compressor after the compressor cylinder has been filled with low pressure gas produced by forming the ice.

5. The process of manufacturing ice in containers in the walls and bottom of which liquid refrigerant is first evaporated and circulated to receive heat for evaporation in an evaporating compartment which consists of stopping the flow of vapor and liquid to said evaporating compartment upon complete freezing of the ice and introducing refrigerant vapor formed by precooling the liquid refrigerant to thaw and loosen the ice.

6. The process of manufacturing ice by admitting and evaporating liquid refrigerant in the walls and bottom of an evaporator container and later thawing the ice loose by introducing vapor formed by precooling the water and refrigerant, said vapor being maintained at an approximately constant pressure intermediate between that in the evaporator and condenser.

7. The process of ice manufacture by evaporating liquid refrigerant in the walls and bottom of a container, the introducing of a thawing vapor for thawing the ice and removing the condensed liquid to the evaporator system without permitting vapor to escape to the evaporator.

8. The process of manufacturing ice by evaporating liquid refrigerant in the walls and bottom of a container and stopping the evaporation in the bottom prior to evaporation in the walls and

introducing a thawing vapor into the bottom prior to introducing it to the side walls and removing the condensed liquid to the evaporator circulating system without permitting the condensing vapor to escape to the evaporator system.

9. Ice making apparatus consisting of a plurality of containers with hollow walls for refrigerant circulation; hollow bottoms with like provision and openings at each end of the bottoms to permit an easy circulation of water up into the container at one end and out at the other end and thru a compartment under and common to all containers in which is located means for circulating the water; means for circulating an evaporating refrigerant thru the walls of the compartments to freeze the ice and means for producing a thawing vapor at a pressure intermediate between that in the condenser and evaporator by reducing the pressure of the liquid leaving the condenser and means for introducing said vapor into the walls and bottom of the compartment for thawing ice.

10. Ice making apparatus consisting of a plurality of containers with hollow walls for circulating evaporating refrigerant, disposed above a common water circulating and sediment collecting tank, means for circulating the water by a longitudinally finned pipe revolving within a partial casing, together with means for circulating the refrigerant while freezing the ice and means for evaporating and precooling the condensed refrigerant in an intermediate pressure cooler and means for introducing the intermediate pressure vapor to the container walls and means to permit escape of liquid from the walls and prevent escape of vapor to the evaporating system.

11. Ice making apparatus consisting of a plurality of containers with hollow walls for circulating evaporating refrigerant, disposed above a single water circulating tank and means for circulating water thru said tank and thru openings in the compartment bottom so disposed as to cause the water to circulate from end to end in the compartments together with means for producing vapor to introduce into the can walls for thawing the ice and means to prevent variation in said pressure by a relief valve interposed between an intermediate pressure receiver and a compressor capable of receiving the gas at this pressure.

12. Ice making apparatus with a plurality of containers with hollow walls for circulating evaporating refrigerant disposed above a common water circulating tank and means for circulating water thru said tank and continuously separating and filtering the water in this tank and provision in the bottom of the containers for circulating the water up into one end of the container thru it and down out at the other end together with means for producing refrigerant vapor at a pressure corresponding to a temperature slightly above that of the melting point of ice by precooling the refrigerant liquid and the icemaking water with means for maintaining that pressure by a pressure control valve interposed between an intermediate pressure receiver (containing a water cooling coil) and a connection to a compressor to receive vapor at the end of a suction stroke at an intermediate pressure together with means for draining all the liquid from the condenser without passing any vapor and means for maintaining a constant level of liquid in the main evaporator and means for stopping the passage of vapor to the evaporator on each compartment and means for introducing the thawing vapor thru the can bottom and thence thru the can walls and of

forcing the liquid out the bottom at the opposite end of the compartment and means for preventing the vapor following the liquid while still permitting the condensing liquid to escape to the 5 evaporating system all substantially as shown.

13. The combination in a refrigerating apparatus including a condenser and a drain trap connected therewith, an intermediate pressure receiver receiving drains from said trap as fast as 10 refrigerant vapors are condensed, constant level

float valves connected with said receiver and drawing liquid from said receiver, low pressure evaporators connected with said valves last mentioned to maintain constant liquid levels in low pressure evaporators, means for removing vapors from evaporators and means for removing vapors from receiver at a pressure intermediate between evaporator pressure and condenser pressure. 5

DOUGLAS KENT WARNER. 10
